UNITED STATES PATENT OFFICE.

MALCOLM B. MOYER, OF MONTEVIDEO, MINNESOTA, ASSIGNOR TO MOYER MANUFACTURING COMPANY, OF MONTEVIDEO, MINNESOTA, A CORPORATION OF MINNESOTA.

CONNECTOR FOR OVERHEAD TRACKS.

1,304,354.

Specification of Letters Patent.

Patented May 20, 1919.

Application filed December 6, 1917, Serial No. 205,793. Renewed October 14, 1918. Serial No. 258,106.

To all whom it may concern:

Be it known that I, MALCOLM B. MOYER, a citizen of the United States, residing at Montevideo, in the county of Chippewa and 5 State of Minnesota, have invented certain new and useful Improvements in Connectors for Overhead Tracks; and I do declare the following to be a full, clear, and exact description of the invention, such as will enable others skilled in the art to which it appertains to make and use the same.

My invention relates to improvements in overhead tracks such as those used for litter carriers, in which it is necessary to operatively connect the rigid track in the barn or other building with the cable track which leads from the building. I am aware that numerous connecting devices have heretofore been devised for such purposes, but 20 they have all possessed certain disadvantages.

First, most of the connectors place the majority of the pull or strain from the cables upon the fixed track which is extremely undesirable. One object of my invention, therefore, is to provide a connector in which the pull of the cable track is resisted by means other than the rigid track.

Second, it has been found that the pull of 30 the cable track is not equalized on both sides of the usual connector, so that the latter is often so twisted as to form a highly undesirable "kink" in the track. A further object of my invention is to overcome any such 35 occurrences as this by substantially equalizing the strain upon opposite sides of the connector or anchor plate by which the inner end of the cable track is secured.

With the foregoing general objects in 40 view, the invention resides in the novel features of construction and unique combinations of parts to be hereinafter fully described and claimed, the descriptive matter being supplemented by the accompanying 45 drawings which form a part of this specification and in which:—

Figure 1 is a vertical section of a portion of a building showing the application of my invention in connecting the cable and rigid 50 tracks;

Fig. 2 is a horizontal section of Fig. 1 on the plane of the line 2—2 thereof;

Fig. 3 is a vertical transverse section on the plane indicated by the line 3—3 of 55 Fig. 1;

Fig. 4 is an edge view of the anchor plate; Fig. 5 is an end elevation thereof;

Fig. 6 is a top plan view of the anchor plate;

Fig. 7 is a detail transverse section on the 60 plane of the line 7—7 of Fig. 2; and

Fig. 8 is a view similar to Fig. 2 but illustrating double instead of single tracks connected by the device.

In the drawings above briefly described, 65 a building B is shown having a doorway D, an upper floor F, and joist J supporting said floor. Within the building B is a rigid litter carrier track R, while a cable track C leads from the building to any required 70 point. Both tracks may be of single form as illustrated in Figs. 1 and 2 or of double form as depicted in Fig. 8, but the action of the improved connector is the same in both cases. This connector is detailed in 75 Figs. 3, 4, 5, 6 and 7 and is constructed as follows:—

A horizontal anchor plate 1 of substantially rectangular shape is provided on its upper side with a pair of vertically extending flanges 2 by means of which it may be secured in a manner to be described. Plate 1 is elongated transversely of the tracks C and R and the opposite ends of said plate are provided with upstanding lugs 3 having 80 cable receiving grooves 4. The lugs 3 occupy approximately half the width of the plate 1 and the other half thereof is provided with suitable supports 5 for the fixed track R, these supports being preferably of the L shape illustrated more particularly in Figs. 5 and 7. An additional lug 6 depends from the plate 1 midway between the lugs 3 and is provided with a cable receiving groove 7 which is located at right angles to the 85 grooves 4. The lower side of plate 1 will also, in most cases, be provided with a longitudinal reinforcing rib 8, this rib and all other parts of the plate being cast in a single piece and requiring no machining whatever.

A suitable hanger 9 depends from certain of the joists J and is secured between the flanges 2 by bolts or the like 10. This hanger may be braced in the direction of pull 105 of the cable track C by a cable 11, one or more rigid brace bars 12, or both, the latter arrangement being illustrated in the drawings. The bars 12 incline upwardly from the connecting device and the lower ends 110

thereof are preferably interposed between the hanger 9 and the flanges 2 and secured in place by the bolts 10, whereas the upper end of said brace bars may well bear against the 5 side of the building, or against a suitable plate 13 provided for strengthening purposes. The lower end of the cable 11 is looped around the depending lug 6, whereas the upper end of said cable is anchored 10 to one of the joists J by a suitable bolt 14 which may be tightened to obtain the required results.

When the cable track C is of the single form illustrated in Figs. 1 and 2, the outer 15 end of said track will be suitably anchored to a post or the like P. The inner portion of the cable, however, is passed downwardly over one of the lugs 3, then transversely beneath the plate 1 and its lug 6, then upwardly over the other lug 3 and finally anchored to a bolt or the like 15, after first 20 extending in substantially the same direction as the main reach or stretch of the track. By this arrangement, as will be clear from 25 Figs. 1 and 2, any twisting strain exerted on the connector by the main stretch of the track, will be resisted by the end of said track which is anchored to the bolt 15 and thus the joint between the cable track and 30 the rigid track will not be affected.

When the device is used in buildings in which the rigid track R is of double form as indicated in Fig. 8, the cable track C will not be anchored to the bolt 15 as above described, but after passage around the improved connector in the manner above set forth, the two ends of said cable track will extend from the building as shown.

The rigid track R may well be secured to 40 the supports or seats 5 in any preferred manner, but for illustrative purposes I have shown J bolts 16 for this purpose (see more particularly Fig. 7). I am not limited to this manner of connecting the rigid tracks 45 to the device and in fact there need be no positive connection between the connector and these tracks, since none of the pull of the cable tracks C is exerted upon the rigid track.

50 From the foregoing, taken in connection with the accompanying drawings, it will be obvious that although my invention is of extremely simple and inexpensive nature, it will be highly efficient and durable. Particular emphasis is laid upon the fact that the improved arrangement of parts does not place any strain from the cable track upon the rigid track. Also, the balanced strain on both ends of the improved anchor or connecting member is of great importance since the pull of the cable track cannot possibly shift the connector so as to disalign the two tracks connected thereby. I also attach great importance to the fact that the entire 55 connector is formed of a single casting and

needs no machining whatever, the several necessary openings being formed during the casting operation, so that even drilling is obviated.

Since probably the best results are obtained from the several specific details shown and described, these details are by preference employed, but I wish it understood that within the scope of the invention as claimed, numerous minor changes may well be made. 75

I claim:—

1. A cable and rigid track connector comprising a horizontal plate and means for anchoring the same, a pair of lugs rising from opposite edges of said plate and each having a cable receiving groove in its upper end, the grooves of said lugs being parallel, a third lug depending from said plate between said pair of lugs, said third lug having a cable receiving groove in its lower end extending at right angles to the aforesaid grooves, the cable track being adapted to pass over said pair of lugs and under said third lug, and means for holding the rigid track in operative relation with said cable 90 track.

2. A cable and rigid track connector comprising a horizontal plate and means for anchoring the same, a pair of lugs rising from opposite edges of said plate and each having a cable receiving groove in its upper end, the grooves of said lugs being parallel, a third lug depending from said plate between said pair of lugs, said third lug having a cable receiving groove in its lower end extending at right angles to the aforesaid pair of lugs and under said third lug, and a pair of seats for the fixed track, said seats being formed on said plate in line with 95 said pair of lugs.

3. A cable and rigid track connector comprising a horizontal plate elongated transversely of the tracks, a pair of vertical flanges cast integrally with and rising from said plate for anchoring the latter, a pair of lugs formed integrally with and rising from the opposite ends of said plate, each of said lugs having a cable receiving groove in its upper end, said grooves formed in the upper ends of said lugs, said grooves being parallel and extending in the direction of the tracks, a third lug depending from said plate midway between said pair of lugs, said third lug having a cable receiving groove in its lower end extending at right angles to the aforesaid grooves the cable track being adapted to pass over said pair of lugs and under said third lug, and a pair of seats for the fixed track, said seats being formed on said plate in line with said 110 pair of lugs.

4. In a cable and rigid track connector, the combination with a cable track, a rigid track aligned therewith and an overhead support; of a hanger depending from said sup- 130

- port and braced thereto in the line of pull of the cable track, an anchor member carried by the lower end of said hanger and extending laterally in opposite directions therefrom, cable seats on the upper side of the laterally extending portions of said anchor member, and additional cable seat on the lower side of said anchor member, said cable track extending downwardly over one of said first named seats, under said additional seat, and upwardly over the other of said first named seats, both ends of said
- 5 cable track extending in substantially the same direction and being anchored, and means for holding the rigid track in operative relation with said cable track. 15
- 10 In testimony whereof I have hereunto set my hand in the presence of two subscribing witnesses.

MALCOLM B. MOYER.
